UNITED STATES PATENT OFFICE

144,769

DESIGN FOR A FOUNTAIN PEN

Darrell C. Crain, Washington, D. C.

Application March 8, 1945, Serial No. 118,333

Term of patent 14 years

(Cl. D74—17)

To all whom it may concern:

Be it known that I, Darrell C. Crain, a citizen of the United States of America and a resident of the city of Washington, in the District of Columbia, have invented a new, original, and ornamental Design for a Fountain Pen, of which the following is a specification, reference being had to the accompanying drawing, forming part thereof, wherein

Fig. 1 is a front elevational view of a fountain pen showing my new design;

Fig. 2, a rear elevation, with the addition of dotted lines to indicate the position of the cap when the pen is being used;

Fig. 3, a side elevation; and

Fig. 4, a top plan view.

I claim:

The ornamental design for a fountain pen, as shown and described.

DARRELL C. CRAIN.
